[57] CLAIM

The ornamental design for a waste basket, as shown and described.

DESCRIPTION

FIG. 1 is a front perspective view of a waste basket showing my new design;

FIG. 2 is an end elevational view, the opposite end being identical thereto;

FIG. 3 is a front elevational view, the rear being identical thereto;

FIG. 4 is a top plan view thereof; and

FIG. 5 is a fragmentary front perspective view of a second embodiment of a waste basket, the only difference residing in the configuration of the top piece.
